UNITED STATES PATENT OFFICE.

JOHN P. FABER AND WALTER MULLER, OF DUNELLEN BOROUGH, NEW JERSEY, AS-SIGNORS, BY MESNE ASSIGNMENTS, TO RANSOME CONCRETE MACHINERY COMPANY, OF PLAINFIELD, NEW JERSEY, A CORPORATION OF NEW JERSEY.

CONCRETE-MIXING MACHINE.

Application filed December 8, 1920. Serial No. 429,049.

To all whom it may concern:

Be it known that we, JOHN P. FABER and WALTER MULLER, citizens of the United States, and residents of the borough of

5 Dunellen, county of Middlesex, State of New Jersey, have invented certain new and useful Improvements in Concrete-Mixing Machines, of which the following is a specification.

10 The improvements relate to rotary drum mixers designed primarily to be used in the mixing of concrete and the like, and more particularly to the means for mixing the materials in the drum and discharging them 15 therefrom. Among the advantages of the improvement are the provision of wings or blades in the interior of the drum, which will quickly and thoroughly mix a relatively large batch of concrete aggregates and 20 deposit them on the discharge chute, and a discharge chute which will receive and discharge the mixed concrete at the end of the mixing operation and direct it into a barrow, chute, or other conduit or receptacle 25 without spilling or splashing, and as fast as the same is deposited thereon by the blades. A further object is to so construct and arrange the discharge chute that it will 30 prevent splashing out or spilling of the liquid or solid aggregates during the mixing operation.

Heretofore it has been common practice to have the blades of concrete mixers so arranged that as the drum rotates they will 35 pick up the aggregates from the lower part thereof and permit them to fall again upon the mass in the bottom in successive portions, each blade as it passes the lowest point and rises picking up a portion and then dumping it from a point at or above mid-height. A usual number of such blades is four, and as they are most advantageously arranged at equal distance from each other they are 40 therefore separated by a mean distance corresponding to the arc of an angle of 90 degrees. The result of such a construction is that when a blade arrives at mid-height or a higher point and begins to discharge its load the preceding blade has 45 reached the highest point in its revolution and has discharged its load, and the greater

part of each load falls from its shelf separately and without coming in contact with the falling load of the shelf above or below it. Another result of such construction is 55 that a relatively large body of the aggregates will be constantly in the bottom of the mixer, thus limiting the capacity of the mixer to the zone below the openings and lengthening the period required for thorough 60 mixing. Still another result is that the mixer must rotate a sufficient number of times to permit the aggregates to be picked up by the limited number of blades and deposited on the discharge chute when the 65 mixing operation is finished and the mixed concrete is to be discharged from the drum. There is also sometimes an accumulation or piling up of the aggregates in the discharge 70 head of the drum due to the fact that discharge scoops of considerable capacity must be located near the discharge end and so constructed that they discharge their load on the chute, which cannot conveniently be extended through the mixer. This also 75 limits the capacity of the mixer and the speed of mixing. There are further a number of other well recognized disadvantages 80 in the present general construction and arrangement of mixing and discharging blades.

With the present improvements the aggregates are taken up rapidly on blades or shelves separated a short distance only and of such length as to permit them to fall at the proper time and in the proper manner, and as two or more blades are always discharging at the same time, at or above mid-height, the aggregates falling therefrom will mingle together and will form a substantially continuous stream. A large part 85 of the batch is also thus continuously in the upper section of a part of the drum, and as the common practice is to charge the drum while it is rotating, the capacity of the drum is the capacity of the portion below the head 90 openings plus the capacity of the ascending blades above that level and plus the amount of aggregates constantly falling from the blades to the bottom. The speed and thoroughness of mixing, the manner in 95 which the aggregates are turned over and commingled, and the capacity of the mixer 100

are thus greatly improved. The discharging operation is also greatly accelerated by the present improvements, and the discharge chute made to take care of this rapid discharge, and also to guard against splashing of the aggregates during the rapid mixing operation. These, and other advantages which will be apparent to those familiar with concrete mixing, are of the greatest importance in the mixing of concrete of every kind, and particularly "dry" concrete which at the present time is very extensively used.

The accompanying drawings illustrate an embodiment of the improvements, and in the said drawings, Figure 1 is a vertical longitudinal section of a mixing drum with the discharge chute and adjacent parts shown in side elevation; Figure 2 is a transverse section of the same, on the line 2—2 of Figure 1, looking in the direction indicated by the arrows; Figure 3 is a diagrammatic view showing the arrangement of the blades on the interior of the drum; Figures 4, 5, 6, and 7 are details of the blades; Figure 8 is a detail of the discharge chute.

The drum 1 is of usual construction and is provided with a charging opening 2 in one head, and a discharge opening 3 in the opposite head. The discharge chute is mounted on the rock shaft 5 supported on a suitable frame to swing through the discharge opening 3, and consists of a chute 4 with arms 6 extending therefrom, and fixed at their outer ends to the said shaft. The inward position of the chute is indicated in Figure 1, and its outward position by the dotted lines in that figure. A fixed extension chute 7 is mounted at the discharge opening and extends from said opening to a point well beyond the same, so as to deliver the materials received from the blades by the chute 4 to a suitable receptacle. This extension chute has a depending portion 8 just inside the flange of the discharge opening, forming a splash plate to prevent materials from escaping through the portion of the opening between the chute and the lower edge of the opening. This splash plate is not connected with the drum, so that it remains stationary while the drum rotates.

At the point where the splash plate 8 joins the extension section of the chute a flat surface 9 is provided, so that when the swinging portion 4 of the chute is in its outward position its inner end will be in contact with or in close proximity to the said surface and parallel therewith. The portion 9 therefore acts as a stop to check the outward movement of the chute, if necessary, and also in connection with the end of the chute forms a seal to prevent materials from splashing out.

The blades 10 extend from the charging opening of the drum to a point near the center thereof and act to move the aggregates toward the discharge opening and toward the lifting and discharging blades 11, which extend from the discharge opening to a point beyond the middle of the drum. The blades 10 are substantially straight, are four in number, and are disposed substantially at right angles to the major portion of the blades 11, but are substantially parallel with the inner turned ends of the said blades. The blades 11 are eight in number, and are arranged in regular order around the periphery, the blades 10 being similarly arranged so that one of them extends between every second pair of the blades 11. The effect of this construction and arrangement is that the aggregates are taken up by the blades 11, moved toward the middle of the drum and dumped from the inner portion thereof downwardly and toward the charging end of the drum where a portion of the said aggregates comes within the influence of the blades 10 and is lifted and moved back toward the blades 11 thereby. A backward and forward diagonal movement is thus imparted to the aggregates while they are being lifted and permitted to fall by the blades. At the same time the aggregates are constantly being lifted by the blades 11 and dumped therefrom at a point at and above mid-height of the drum, the aggregates from three of the blades falling to the bottom simultaneously at all times, and a large portion of the aggregates being constantly in the upper part of the drum. This insures a quick and thorough mixing of the aggregates and increases the normal capacity of the drum, since the drum is constantly in rotation during the charging, mixing, and discharging operations.

It will be seen that of the materials taken up by the blades 11 the first portion to be discharged therefrom is that portion on the upwardly extending part of the blades nearest the discharge head, and that these materials will fall over the materials in the bottom portion of the blades in the direction of the blades 10, by which they are returned so as to pass beneath the falling materials in the lower part of the blades 11. This insures that the materials at the top of the mass in the bottom of the mixer are constantly moved and directed in such a manner as to pass to the lower part thereof.

The width of the blades 11 at their lowest part is slightly greater than the distance between these blades, and the result of this is that the load lifted by each blade extends substantially to the bottom of the next blade above it. By this arrangement a substantially continuous mass of aggregates constantly extends well above midheight of the

drum and a substantially continuous downpour of these aggregates falling from the blades is maintained. At the same time the aggregates taken up by each blade from the top of the mass in the bottom of the drum is discharged therefrom simultaneously with and mingles with the middle portion of the blade next above and the bottom portion of the blade next above that, so that the stream 10 of aggregates falling from the blades is composed of aggregates taken from all levels of the mass at the bottom mingled together. This is true of the portion which is directed toward the charge opening and 15 within the influence of the blades 10, as well as the portion which falls in a direct vertical path. The action of the blades or scoops 11 in diverting the aggregates laterally to a certain extent is brought about 20 largely by the steeper and longer side of each blade next to the head of the drum, which is also of greater diameter as well as greater length than the portion extending toward the charging opening.

25. The inwardly turned edge 12 of the chute 4 is on the side opposite the side of the mixer on which the blades 11 ascend, and the opposite side of the chute is cut away on a line inclined from the arm 6, to the 30 inner end of the chute, the inturned portion increasing in width in the opposite direction. The result of this is that the aggregates discharge toward the chute by the blades or scoops 11, and moving laterally to 35 some extent will pass over the near side of the chute and be caught by the inwardly turned opposite side 12, so that the chute will catch a maximum volume of the mixed concrete and permit none of it to spill over 40 therefrom.

Another feature of construction resides in the fact that the blades are approximately equal to the annular flange formed by the heads with their central openings. This 45 gives them a lifting capacity equal to a large percentage of the capacity of the drum below the openings, and the result is that a large portion of the contents of the mixer are constantly elevated above the mass in 50 the bottom.

What we claim is:

1. In a mixer the combination of a rotatable drum having a hollow cylindrical body and heads with charging and discharging 55 openings therein, a series of blades extending from a point near the discharge opening to the medial part of the drum on the interior thereof, the said blades being wider at their medial portions than at their ends having one edge secured to the inner side of the cylindrical portion and extending inwardly therefrom and being bent longitudinally intermediate their ends to form lifting and mixing scoops, a series of blades simi- larly secured and positioned extending inwardly from the head with charging opening and having their inner ends approximately in circumferential line with the inner ends of the first named blades, but not overlapping and being disconnected and 60 spaced therefrom on said circumferential line.
2. In a mixer the combination of a rotatable drum having a hollow cylindrical body and heads with charging and discharging 65 openings therein, a series of blades extending from a point near the discharge opening to the medial part of the drum on the interior thereof, the said blades having one edge secured to the inner side of the cylindrical portion and extending inwardly therefrom and being curved longitudinally intermediate their ends to form lifting and mixing 70 pockets or scoops, the radial width of said blades being substantially equal to their mean distance apart, and the distance between each of the blades and the blades nearest it in the series being approximately 75 equal to one-eighth of the circumference of the cylindrical portion, the said parts being 80 constructed and arranged to maintain a continuous stream of materials falling from a plurality of said blades at and above the axis thereof.
3. In a mixer the combination of a rotatable drum having a hollow cylindrical body and heads with charging and discharging 85 openings therein, a series of blades extending from a point near the discharge opening to the medial part of the drum on the interior thereof, the said blades having one edge secured to the inner side of the cylindrical portion and extending inwardly therefrom and being curved longitudinally intermediate 90 their ends to form lifting and mixing pockets or scoops, the radial width of said blades being substantially equal to their mean distance apart, the said parts being 95 constructed and arranged to maintain a continuous stream of materials falling from a plurality of said blades at and above the axis thereof, said blades having a portion between the discharge opening of the drum and the curved portion at an acute angle to 100 the head of the drum, and the portion extending between said curved portion and the inner end being approximately at right angles to the first named portion, but shorter than said first named portion, the said parts being 105 so constructed and arranged that materials discharged from said blades is caused to move laterally toward the charging opening, and other blades similarly mounted extending from a point near the charging opening to the medial portion of the drum in substantially the opposite direction to the direction of the longer portion of 110 the first named blades, and so constructed 115
4. In a mixer the combination of a rotatable drum having a hollow cylindrical body and heads with charging and discharging 120 openings therein, a series of blades extending from a point near the discharge opening to the medial portion of the drum on the interior thereof, the said blades being wider at their medial portions than at their ends having one edge secured to the inner side of the cylindrical portion and extending inwardly therefrom and being bent longitudinally intermediate their ends to form lifting and mixing 125 pockets, a series of blades similarly secured and positioned extending inwardly from the head with charging opening and having their inner ends approximately in circumferential line with the inner ends of the first named blades, but not overlapping and being disconnected and spaced therefrom on said circumferential line.

that materials discharged from the said first named blades are moved back toward the charging opening thereby.

4. The combination of a rotatable drum having a hollow cylindrical body and heads with charging and discharging openings therein, a series of blades extending from a point near the discharge opening to the medial part of the drum on the interior thereof, said blades having a greater width intermediate their ends than at both ends, and being curved to form pockets between the middle of the drum and its discharge end, and other blades extending from the charging opening to the medial part of the drum and having their inner ends terminating in proximity to the inner ends of the first named blades, but in spaced relation thereto, the ends of the second blades being located between ends of the first blades.

5. In a mixer the combination of a rotatable drum having a hollow cylindrical body and heads with charging and discharging openings therein, a series of blades extending from a point near the discharge opening to the middle of the drum on the interior thereof, the said blades having one edge secured to the inner side of the cylindrical portion and extending inwardly therefrom and being bent longitudinally and having a widened portion intermediate their ends to form lifting and mixing scoops, a series of relatively straight blades similarly secured and positioned extending inwardly from the head with charging opening to a point near the middle of the drum and having their inner ends reduced in width and approximately in circumferential line with the inner ends of the first named blades, but being disconnected and spaced therefrom and not overlapping.

6. The combination with a hollow cylindrical drum having a discharging opening, of a swinging chute and a fixed discharge chute mounted exterior to the drum, a pivoting member located outside the drum upon which said chute is pivoted at its outer portion and swings and a rigid connection between the said chute and its said pivot, the parts being so constructed and arranged that the chute swings from a position inside the drum to an inverted position outside the drum by swinging motion on its pivot alone.

7. The combination with a hollow rotatable drum having a discharge opening, of a chute mounted at such opening and adapted to convey materials therethrough, blades mounted on the interior of said drum and arranged to ascend on one side and descend on the other side of said chute with the rotation of the drum, said chute having a substantially flat bottom a longitudinal upwardly extending flange on the side opposite the side on which the blades ascend disposed

at approximately a right angle to said bottom and a flange on the other side of inferior width.

8. The combination with a hollow rotatable drum having a discharge opening, of a chute mounted at such opening and adapted to convey materials therethrough, blades mounted on the interior of said drum and arranged to ascend on one side and descend on the other side of said chute with the rotation of the drum, said chute having a substantially flat bottom a longitudinal upwardly extending flange on the side opposite the side on which the blades ascend and a flange on the other side of inferior width, said flange on the other side also tapering toward the inner end of the chute.

9. The combination of a rotatable drum having a hollow cylindrical body and heads with charging and discharging openings therein, a series of blades extending from a point near the discharge opening to the medial part of the drum on the interior thereof, and being curved to form pockets between the middle of the drum and its discharge end, and other blades extending from the charging opening to the medial part of the drum and having their inner ends terminating in proximity to the inner end of the first named blades, but in spaced relation thereto, the ends of the second blades being located between ends of the first blades, and said second blades being wider at the charging end of the drum than at the other end, being substantially straight from end to end and radial from side to side.

10. The method or process of mixing concrete aggregates in a drum, which consists in elevating several portions of the said aggregates successively, so that the said portions are in elevated positions simultaneously one above another and simultaneously discharging the upper part of each lifted portion with the middle part of the portion next above it and the lower part of the portion next above that, and permitting them to fall to the bottom of the drum in a continuous stream, thus causing said parts to intermingle while falling, and the upper part of each portion of aggregates to mingle with the middle and lower parts of other portions.

11. In a mixer the combination of a rotatable drum having a hollow cylindrical body and heads with charging and discharging openings therein, a series of blades extending from a point near the discharge opening to the middle of the drum on the interior thereof, the said blades having one edge secured to the inner side of the cylindrical portion and extending inwardly therefrom and being bent longitudinally and having a widened portion intermediate their ends to form lifting and mixing scoops, a series of

relatively straight blades similarly secured and positioned extending inwardly from the head with charging opening to a point near the middle of the drum and having their inner ends approximately in circumferential line with the inner ends of the first named blades, but being disconnected and spaced therefrom and not overlapping, the inner

ends of both sets of blades being reduced in width. 10

Witness our hands this 30th day of November, 1920, at Dunellen, in the county of Middlesex, State of New Jersey.

JOHN P. FABER.
WALTER MULLER.
